UNITED STATES PATENT OFFICE.

LUTHER SMITH, OF NORRISTOWN, PENNSYLVANIA, ASSIGNOR OF THREE-TENTHS PER CENT TO DAVID GREEN, TWO-TENTHS PER CENT TO MILES ABNEY, ONE-TENTH PER CENT TO JAMES BROWN, ONE-TENTH PER CENT TO PLUMMER NEAL, ONE-TENTH PER CENT TO ABRAHAM D. DAVENPORT, AND ONE-TENTH PER CENT TO JESSE HERBERT, ALL OF NORRISTOWN, PENNSYLVANIA.

RAILWAY TIE.

Application filed November 6, 1925. Serial No. 67,439.

To all whom it may concern:

Be it known that I, LUTHER SMITH, a citizen of the United States, residing at Norristown, in the county of Montgomery and State of Pennsylvania, have invented certain new and useful Improvements in Railway Ties, of which the following is a specification.

This invention relates to railway ties and more particularly to reinforced railway ties.

An object of the invention is to provide a reinforced concrete railway tie with means for locking rails thereupon.

Another object of the invention is to provide a reinforced concrete tie having means thereupon for securing a rail in a fixed position, whereby the laying of a track is greatly facilitated.

A further object of the invention is to provide a reinforced concrete tie having thereupon means for securing rails thereupon in a fixed position, the means for securing the rails in a fixed position being formed upon the tie so as to securely lock the rails thereupon at a standard gage.

A further object of my invention is to provide a reinforced concrete tie having thereupon a locking member partially embedded in the tie, and provided with means for mounting and securing in a locked position an adjustable member, whereby a rail may be securely clamped and supported.

A still further object of my invention is to provide a reinforced concrete railway tie provided with a positive locking means, and to so construct the same that it will be highly efficient in operation, yet of marked simplicity as a whole and in respect to each of its component parts, so that its manufacture is economically facilitated both as regards parts and their assembly.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the ac-

companying drawings means for carrying the same into practical effect, without limiting the improvements in their useful applications to the particular constructions, which for the purpose of explanation, have been made the subject of illustration.

In the drawings forming a part of this specification:

Figure 1 is a perspective view illustrating one end of my improved tie, a section of the rail being shown clamped thereto;

Fig. 2 is a perspective view of the locking means detached from the tie and disassembled;

Fig. 3 is a side elevation of the locking mechanism in a closed or locked position.

Referring by numerals to the drawings, 1 represents a railway tie constructed in accordance with my invention. The tie comprises a rectangular concrete casting having a plurality of reinforcing rods 2 embedded therein. The side faces of the rectangular concrete member are provided with oppositely disposed and corresponding dovetail slots or channels 3, at each end thereof.

Mounted upon the rectangular concrete member at each end thereof is a plate or saddle 4. The plate 4 is bent to straddle and to conform with the concrete member 1. The plate 4 is provided upon its face 5 with a flange 6 adapted for engagement with a flange of a rail 7. The plate 4 has oppositely disposed flanges 8 at right angles to the body portion. Formed upon the ends of the flanges 8 are oppositely disposed dovetailed channels 9 which engage or fit into the channels 3 in the rectangular concrete member 1. The plate 4 is further provided with a boss or lug 10 having an aperture 11, the object of which will hereinafter appear.

The plate 4 is a stationary member and is positioned or adjusted to the rectangular concrete member 1 at the time of casting the concrete member, however, the plate 4 may be mounted upon the rectangular concrete member after the casting of the member has been completed, in which event the plate 4 would be secured to the concrete member 1 by a transverse bolt, not shown.

An adjustable plate or saddle 12 is bent to straddle the rectangular concrete member 1. The plate 12 is provided upon its top

with a flange 13 adapted to engage a flange on the base of a rail. The flange 13 is oppositely disposed with respect to the flange 6 upon the stationary plate 4, when the parts 6 are assembled. The plate 12 has oppositely disposed and corresponding right angular flanges 14 which engage the side faces of the concrete member 1. The flanges 14 are provided upon their free ends with dovetail guides 15, oppositely disposed with respect to each other. The guides 15 are adapted to engage the guideways 9 upon the plate 4. The side flanges 14 are further provided with bosses having apertures 16 10 therein. The apertures 16 register with the apertures 11 in the stationary plate 8. Bolt 17 passes through the apertures 11 and 16. Taps 18 are threaded upon the bolts 17. By means of the bolt 17, the members 4 and 12 are securely locked together in such a manner as to rigidly support rails 7, and to securely lock the same upon the rectangular member 1 in a predetermined spaced relation which will in the general run of cases 20 be the standard gage.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the 30 scope of the appended claims.

Having thus described the various features of my invention, what I desire to secure by Letters Patent is:—

1. A railway tie comprising a reinforced 40 concrete tie having oppositely disposed corresponding dovetailed slots formed in its side faces.

2. A railway tie comprising a rectangular concrete mass, a plurality of reinforcing 45 bars embedded within the concrete mass and oppositely disposed corresponding dovetailed slots formed in the sides of the concrete mass.

3. A railway tie comprising a rectangular 50 concrete member, a plurality of reinforcing bars embedded in the concrete member, and corresponding oppositely disposed dovetail slots formed in the side faces of the concrete member at each end thereof.

55 4. A railway tie comprising a rectangular concrete member, a plurality of reinforcing bars embedded in the concrete member, oppositely disposed corresponding dovetail slots formed in the side faces of the concrete member, a plate adapted to straddle the concrete member, guideways formed integral with the plate adapted to engage the slots in the concrete member, a flange upon the upper face of the plate, a second plate adapted 60 to straddle the concrete member, lugs

upon the second plate adapted to engage the guideways carried by the first mentioned plate, a flange upon the second mentioned plate oppositely disposed to the flange upon the first mentioned plate and means for securing the plates together. 70

5. A railway tie comprising a rectangular concrete member, a plate bent to clamp over the concrete member, a flange upon the upper surface of the plate, dovetail slots formed upon the sides of the plate, the dovetail slots embedded within the cement member, a second plate bent to clamp over the concrete member, a flange upon the second plate oppositely disposed with respect to the flange upon the first mentioned plate, dovetailed flanges upon the second mentioned plate adapted to engage the slots in the first mentioned plate and means for securing the plates together. 75

6. A railway tie comprising a rectangular reinforced concrete member, a plate mounted upon the concrete member, guideways formed upon the plate, the guideways embedded in the concrete member, a flange upon the top of the plate, an adjustable plate bent to straddle the concrete member, guides upon the adjustable plate engaging the guideways, a flange upon the top of the adjustable plate oppositely disposed with respect to the flange upon the plate first mentioned and means for securing the plates together. 80

7. A railway tie comprising a rectangular reinforced concrete member, a plate mounted in a fixed position upon the concrete member, a flange upon the top of the plate, guideways upon each end of the plate, an adjustable plate having guides mounted in the guideways, a flange upon the adjustable plate oppositely disposed to the flange upon the stationary plate and means for securing the plates together. 100

8. A railway tie comprising a rectangular reinforced concrete member, a plate mounted upon the tie in a fixed position, a flange upon the top of the plate, guideways integral with the plate, the guide ways embedded in the concrete member, an adjustable plate having guides mounted in the guideways, a flange upon the adjustable plate oppositely disposed to the flange upon the fixed plate and means for securing the plates together. 105

9. A railway tie comprising a rectangular reinforced concrete member, a plate stationarily mounted upon the concrete member, guideways integral with the stationary plate, a plate having guides adjustably mounted in the guideways, oppositely disposed flanges carried by the stationary and adjustable plates, and means for securing the plates together. 115

10. A railway tie comprising a rectangular concrete member, a plurality of reinforce- 120

ing bars embedded in the concrete member, oppositely disposed corresponding dovetail slots formed in the side faces of the concrete member, a plate adapted to straddle the concrete member, guideways formed integral with the plate adapted to engage the slots in the concrete member, a flange upon the upper face of the plate, a second plate adapted to straddle the concrete member, lugs upon the second plate adapted to engage the guideways carried by the first mentioned plate, a flange upon the second mentioned plate oppositely disposed to the flange upon the first mentioned plate and means for securing the plates together to engage and lock the rails on standard gauge.

11. A railway tie comprising a rectangular concrete member, a plate bent to clamp over the concrete member, a flange upon the upper surface of the plate, dovetail slots formed upon the sides of the plate, the dovetail slots embedded within the cement member, a second plate bent to clamp over the concrete member, a flange upon the second plate oppositely disposed with respect to the flange upon the first mentioned plate, dovetailed flanges upon the second mentioned plate adapted to engage the slots in the first mentioned plate and means for securing the plates together, to engage and lock the rails on standard gauge.

12. A railway tie comprising a rectangular reinforced concrete member, a plate mounted upon the concrete member, guideways formed upon the plate, the guideways embedded in the concrete member, a flange upon the top of the plate, an adjustable plate bent to straddle the concrete member, guides upon the adjustable plate engaging the guideways, a flange upon the top of the

adjustable plate oppositely disposed with respect to the flange upon the plate first mentioned and means for securing the plates together, to engage and lock the rails on standard gauge.

13. A railway tie comprising a rectangular reinforced concrete member, a plate mounted in a fixed position upon the concrete member, a flange upon the top of the plate, guideways upon each end of the plate, an adjustable plate mounted in the guideways, a flange upon the adjustable plate oppositely disposed to the flange upon the stationary plate and means for securing the plates together to engage and lock the rails on standard gauge.

14. A railway tie comprising a rectangular reinforced concrete member, a plate mounted upon the tie in a fixed position, a flange upon the top of the plate, guideways integral with the plate, the guideways embedded in the concrete member, an adjustable plate mounted in the guideways, a flange upon the adjustable plate oppositely disposed to the flange upon the fixed plate and means for securing the plates together to engage and lock the rails on standard gauge.

15. A railway tie comprising a rectangular reinforced concrete member, a plate stationarily mounted upon the concrete member, guideways integral with the stationary plate, a plate adjustably mounted in the guideways, oppositely disposed flanges carried by the stationary and adjustable plates, and means for securing the plates together to engage and lock the rails on standard gauge.

In testimony whereof I affix my signature.

LUTHER SMITH.
